CLEANING NOZZLE

ATLANTIC FURNACE, PROVIDENCE, R. I.
Application August 27, 1925. Serial No. 1,521,421

CLEANING NOZZLE

This invention relates to a cleaning nozzle; and has for one of its objects the provision of a nozzle which may be utilized for cleaning purposes by means of air pressure rather than by some 5 electric motor for creating a suction.

Another object of the invention is the provision of a portable cleaning nozzle which may be connected to an internal combustion engine of an automobile in such a manner that the running of the engine will supply the power necessary for the operation of the nozzle for cleaning the upholstery of the automobile itself, or other adjacent or nearby objects within the reach of a flexible conduit.

15 Another object of the invention is the novel formation of the nozzle itself which will enable it to be inexpensively manufactured with air distributed about the same for efficient operation and ejection of dirt or the like which is picked up.

20 Another object of the invention is the easy control of the device by means of a trigger action of an actuated valve directly adjacent the nozzle and hand of the operator.

With these and other objects in view, the invention consists of certain novel features of construction, as will be more fully described, and particularly pointed out in the appended claim.

In the accompanying drawing:

Fig. 1 is a perspective view of the nozzle:

Fig. 1 is a perspective view of the nozzle,
30 Fig. 2 is a central sectional view through the
nozzle.

Fig. 3 is an end view of the mouth portion of the nozzle with the tip removed:

Fig. 4 is an end view of the inner surface of the nozzle tip:

Fig. 5 is an end view of the outer surface of the nozzle tip:

Fig. 6 is a sectional view of the tip of the nozzle on line 6-6 of Figure 5:

40 Fig. 7 is a sectional detailed view through the valve mechanism of the control for the air pressure supply conduit.

Fig. 8 is a fragmental view of a portion of an automobile with my device applied thereto and illustrating one use thereof.

49 illustrating one use thereof.
The usual vacuum cleaning device on the market consists of an electric motor with an evacuating or exhausting fan for sucking air through a conduit with a nozzle at its end for picking up
50 particles of dirt or the like; and in order that there may be a nozzle which may be attached to an internal combustion engine for obtaining the power necessary to operate the same and one which may be effectively used for the cleaning
55 of the automobile upholstery therein without a

great deal of additional apparatus, and also one which may be used in and about objects adjacent the automobile, I have provided a nozzle which may be operated by the pressure developed by the piston of the engine cylinder of the automobile; and the following is a more detailed description of the present embodiment of this invention, illustrating the preferred means by which these advantageous results may be accomplished:—

With reference to the drawing, 10 designates generally the body of the nozzle which is flared at one end 11 and extended in the opposite direction to provide a conduit 12 extending therefrom, having a conducting passage 13 which will connect with a suitable collecting bag 14 attached to one end thereof.

This flared end 11 presents an elongated mouth or collecting chamber 15 having a thickened wall portion 16 which is provided with an end surface 18 in a single plane and an outwardly facing groove 17 in this surface. A tip designated generally 19 is provided with a face surface 20 to contact or abut the surface 18 with an air tight fit. This tip 19 is also provided with a groove 21 which matches up with a groove 17 in the body and which grooves together provide a conduit 22 which extends generally about the elongated mouth opening 15.

One or more jets in bosses 23 communicate with the conduit 22 and are inclined to direct the fluid in the conduit and under pressure upwardly and along the conduit 12 or 13 and cause particles to be drawn in through the mouth 15 that may be adjacent thereto. These jets are shown as located on opposite sides of the mouth 18 but may also be bored in the bosses 23' at the ends of the mouth, if desired. In order that air pressure be supplied to the conduit 22 I have provided a passage 24 in the thickened portion 25 of the body, which passage communicates with the bore 26 in the handle portion 27, the same being controlled by a valve 28 and pressure being supplied through the coupling 29 from some suitable source of supply.

The control valve 28 is lodged within a bore 30 in the handle and comprises a suitable valve seat 31 supported by the threaded plug 32, there being a conical valve 33 to fit the seat 31 which is provided with a stem 34 extending through the plug 32 and provided with an extension 35 which tends to centralize the spring 36 forcing the valve 33 to its seat. The tension on the spring may be adjusted by the threaded plug 37 having a slotted head 38. The valve stem 34 is forced inwardly from its seat by a trigger lever 39 having a curved 55

portion 48 to fit the operator's finger and permit air to pass from the bore 26 through the valve seat and the ports 44 into the conduit 24 and thence through the jets 23 and back along the 5 exhaust conduit 18.

The handle 27 is provided with spaced notch portions as at 42 to fit the hand of the operator so that the same may be nicely gripped.

The tip designated generally 18 is provided with 10 grooves 44 in its face in which a brush 45 is located, which in cooperation with the air sucked in through the mouth 18 serves to dislodge particles on upholstery or other surfaces which are desired to be cleaned and cause them to be 15 passed and discharged through the exhaust conduit 18.

Any suitable air pressure may be coupled to the bore 26 by coupling 28, but a specific use for 20 which this nozzle is intended is a connection to the internal combustion engine 47 of an automobile or motor vehicle, the internal combustion engine being of the usual type having cylinders and pistons with spark plugs 48 for each piston.

To attach the device to the engine it is merely 25 necessary to remove but one of the spark plugs 48 and thread into the opening thus left a coupling 49 to which the tubular hose 50 is connected. As the engine operates, the compression in the cylinder from which the spark plug is removed will 30 be forced through the conduit 50 and will enter the bore 26 where it may accumulate as a storage chamber to be supplied to the nozzle under control of the valve trigger lever 38.

By this arrangement a unique and simple device is provided which may be a part of the equipment of any automobile and which may be easily attached for cleaning the upholstery of the automobile or by means of a longer hose may be utilized by some portion adjacent the automobile for the cleaning of adjacent devices as occasion may require or dictate.

The foregoing description is directed solely towards the construction illustrated, but I desire it to be understood that I reserve the privilege of resorting to all the mechanical changes to which the device is susceptible, the invention being defined and limited only by the terms of the appended claim.

A cleaning nozzle comprising a hollow body having an inlet opening into said body and an exhaust conduit extending from said body, the end of the body including the inlet opening being formed as a removable tip, a conduit extending along both sides of the nozzle at the juncture of the tip and main portion of the body comprising a groove in the body and a groove in the tip, oppositely placed bosses projecting into said inlet opening having apertures connecting with said conduit, said apertures extending in the direction of the exhaust and affording coplanar intersecting jets, and a pressure supply conduit in said body communicating with the groove in said body.

FRANK PATALANO.
